KNITTING MACHINE

Henry Harold Holmes and John Cyril Herbert Hurd, Leicester, England, assignors to Wildt and Company Limited, Leicester, England, a British company

Application July 15, 1942, Serial No. 451,044
In Great Britain July 25, 1941

14 Claims. (Cl. 66—135)

This invention appertains to knitting machines and has reference particularly to such machines of the type adapted to produce knitted fabric with purl effects.

The object of the invention is to improve knitting machines of the type referred to in such a way as to increase their patterning scope as will be hereinafter described.

According to this invention a knitting machine of the type concerned is equipped with stitch or loop transferring instruments, means for operating the same, and lap or wrap striping or embroidery mechanism.

The invention may be applied to a flat or a circular links and links knitting machine, i. e. a machine having two needle beds with double-ended needles which are actuated indirectly through jacks or sliders so as to enable needles to be transferred from one bed to the other for the purpose of enabling loops to be cast off the needles in one direction on one course and in the reverse direction on another course. Thus by appropriate prearranged or selective transfer of needles from one bed to the other certain needles can be caused to produce purl stitches while others knit plain stitches and many and diverse purl stitch effects can be produced, for which purpose the machine may be equipped with automatically controlled transfer cams, or selective needle transfer mechanism for action upon butts on the jacks or sliders in the manner well understood in the art. In pursuance of the invention such a machine is also equipped with stitch or loop transferring mechanism and with lap or wrap striping or embroidery mechanism which may be of any appropriate character adapted to suit the requirements of the machine to which it is to be applied, for the purpose of supplying an embroidery thread or threads to prearranged or selected needles.

The stitch or loop transferring mechanism may be of the form comprising an appropriate number of transfer instruments independently operable in conjunction with the plain needles of the machine, and means for operating the said instruments suchwise that upon actuation thereof the transference of loops from desired wales to adjacent wales is effected. Preferably these instruments are so formed and arranged as to be adapted upon appropriate actuation thereof to effect the transference of sinker wale loops to adjacent needle wales to form pelerine stitches. Sinker wale loops by reason of such transference are, of course, meshed with adjacent knitted loops as a result of which holes or

eyelets are formed in the sinker wales. Accordingly, by effecting loop transference at different wales and in different courses a diversity of openwork effects can be produced.

5 The transfer instruments may be of any form suitable for the intended purpose. Advantageously, however, the said instruments may be formed at their operative ends with laterally offset or like loop-expanding portions adapted to position loops thereon for engagement by needles to which transference is to be effected. For example, each instrument may have a curved, bowed or arched formation the opposite ends of which are substantially in the same 15 straight line.

If desired, the instruments may be used in pairs, i. e. left hand and right hand, so as to enable a loop thereon to be spread laterally in opposite directions for transference to adjoining 20 needles.

To enable a diversity of pattern or fancy effects to be produced the transfer instruments may be selectively operated, such for example as by means of a patterning device or pattern 25 controlled cams or other parts or members adapted to operate upon butts on the instruments.

The lap or wrap striping mechanism may be of that form comprising any suitable number 30 of individually operable thread guides, e. g. one for each needle, or a plurality of needles, means for selectively operating the said guides and means for operating the needles so that selected threads are lapped or wrapped round corresponding needles, whereby when said needles are caused to knit, embroidery stitches are produced by said needles in addition to stitches formed of the main yarn or yarns ordinarily supplied. Alternatively, means may be provided for selectively 35 operating needles, e. g. advancing or reTRACTING them in relation to the guides, so that only desired needles receive embroidery threads.

In the case of a multi-feeder circular links and links knitting machine, all of the lap or wrap thread guides may be continuously actuated seriatim and, starting with all of the needles in the plain cylinder, selected needles may be transferred to the rib cylinder, so that at a following feeder the needles so transferred draw 45 loops in the rib direction to produce pattern effects and only the plain, i. e. unselected, needles are wrapped with embroidery thread. In this instance, although lap or wrap thread guides move out between those needles knitting in the 50 rib cylinder, the presence of said needles will 55

prevent the guides from completing their wrapping action so that as a consequence they will be withdrawn at the same side of the needles at which they moved out.

The invention may be applied to knitting machines having a single feed or two or more feeds, of either the rotary or stationary needle cylinder type and having latch or bearded needles.

In order that the invention may be more clearly understood and readily carried into practical effect, an example thereof applied to a circular links and links knitting machine of the superposed rotary needle cylinder type will now be described with reference to the accompanying 15 diagrammatic drawings, wherein,

Figure 1 is a vertical sectional view of so much of the said machine as is necessary to illustrate the application thereto of the present invention.

Figure 2 is a detail vertical sectional view showing one of the pelerine instruments within the dial and the collecting track to which operating butts on selected ones of said instruments are directed as will be hereinafter described,

Figure 3 is a plan view partly in section of so much of the dial cam system of the machine (with a portion of the dial cam plate broken away) as is necessary to show the cams at two feeds for actuating both the pelerine instruments and the lap or wrap thread guides,

Figure 4 is a detail transverse sectional view taken on the line VII—VII of Figure 3 showing a door in the dial cam cap for the purpose hereinafter specified,

Figure 5 is a development of the plain and rib knitting cam systems of the machine at the said two feeds,

Figure 6 is a detail vertical sectional view showing the rotary selecting device employed in the selective transference of needles from the 40 plain cylinder to the rib cylinder to produce purl stitches.

Figure 7 depicts the form of inside holding down sinker or web holder provided at the point where transfer instruments are advanced for the transference of loops to needles,

Figure 8 shows the said sinker or web holder as it appears when moved forwards, and

Figures 9 and 10 are plan and side-elevational views respectively of the constructional form of shogging mechanism shown in Figure 1.

Like parts are designated by similar reference characters throughout the drawings.

In Figure 1 the rotary plain (bottom) and rib (top) cylinders of the machine are indicated at 2 and 3 respectively. One of the double-ended needles is shown at 4, and 5 and 6 represent bottom and top needle-operating sliders by means of which the stitch forming movements are imparted to the said needle and also by means of which the needle can be transferred from one cylinder to the other, it being understood that needles are transferred from the plain cylinder 2 to the rib cylinder 3 in order to produce ribbed fabric and purl stitches, according to requirements.

For selecting the needles 4 for transference to the rib cylinder 3 to produce purl stitch effects, the machine may conveniently be equipped with selective needle transfer mechanism of the form described in prior United Kingdom specification No. 391,212. Thus, there is provided for action on the knitting butts 7 of the bottom sliders 5 one or more patterning units such as that indicated at 8 in each of Figures 5 and 6. The or

each patterning unit consists of a rotary selecting device comprising a sleeve 9 (Figure 6) in which pivoted needle engaging jacks 10 are carried. This sleeve is fixedly mounted on an obliquely disposed axis and adapted to be positively driven from the rotary plain cylinder 2. The jacks 10 engage the knitting butts 7 aforesaid and are themselves actuated selectively by means of a pin drum or equivalent, in a manner fully described in United Kingdom specification No. 282,904, to effect the required selection of the bottom sliders 5. Associated with the or each patterning device 8 is an auxiliary transfer cam 11.

The machine has a plurality of feeds, e. g. four. The development of the knitting cam systems at two feeds J and J¹ is shown in Figure 5. Of these two feeds, J¹ is a plain feed and J a design feed. It will be observed that the pattern device 8 is located just beyond the plain feed, i. e. between the two feeds in the direction of rotation of the needles which is indicated by the arrow K. The rib and plain knitting cam systems indicated generally by the references L and M respectively at each of the feeds are of usual construction and arrangement. During the production of fabric with purl stitch effects or purl designs all of the needles 4 knit plain at the feed J¹ and, by reason of the selective action of the pattern device 8 at the design feed J, selected needles form purl and the remaining needles form plain stitches to produce purl fabric. For example, referring to the feed J¹, assume that all of the needles are in the plain cylinder 2 and that the knitting butts 7 of their bottom sliders 5 are being acted upon by the plain stitch cam 12 of system M, while the knitting butts 13 of the top sliders 6 are passing idly over the rib stitch cam 14 of system L. Then, as the bottom sliders 5 travel in the direction of the arrow K, the knitting butts 7 leaving the plain feed J¹ will be engaged by a cam 24' whereby the said sliders will be raised to clearing height and their knitting butts thereby brought into the range of the pattern device 8. The latter will thereupon act selectively upon the butts 7 as shown at N so that the corresponding lower, i. e. transfer, butts 15 will be landed onto the auxiliary transfer cam 11 as shown at O whereby the corresponding needles will be caused to be engaged by the corresponding top sliders 6 which are positioned at clearing height by a cam 16 acting on their knitting butts 13. The non-selected bottom sliders will, of course, remain at clearing height as shown at P so that their transfer butts 15 pass below the cam 11 as shown at Q. The result is that at the next feed, i. e. the design feed J, selected needles are caused to knit in the rib cylinder 3 while the remaining needles knit in the plain cylinder 2. In a machine having four or a larger even number of feeds, by reason of the provision of a pattern device adjacent to alternate feeds, all the needles may be caused to knit plain at alternate feeds, while at the intermediate design feeds selected needles form purl stitches, and the non-selected needles form plain stitches. In a two feed machine having only one pattern device 8, all of the needles would knit plain at one feed while at the other feed selected needles would knit purl and the remainder would knit plain.

After disengagement of the needles from the selected sliders the latter are pulled down again as they approach the feed J by action of a cam edge 17 on the butts 15. The character of patterning just described produces a plain pattern on a ground of ordinary purl. If, however,

it is desired to produce ribbed patterned effects on a machine having two or more feeders and furnished with a pattern device at one of said two feeders, or at each of the alternate feeders, as the case may be, it is within the scope of the invention to cause needles selected at the or each patterning feeder to draw loops in the rib direction at the adjacent or at the next non-patterning feeder.

The transfer of needles from the rib cylinder to the plain cylinder, as and when required, may be effected in the usual manner. For the purpose of transferring needles from the plain cylinder to the rib cylinder for rib knitting, transfer cams of usual construction and arrangement—in addition to the patterning means—are preferably provided. Thus, in the illustrative arrangement depicted in Figure 5, transfer cams 18, 19 and 20 are provided in the top cam box. The cam 18 effects the transference of the selected needles back to the plain cylinder 2 after knitting in the rib cylinder 3 at the design feed J, preparatory to knitting in the cylinder 2 at the plain feed J¹. A bottom transfer cam 21 is provided just beyond the auxiliary transfer cam 11.

A welt cam such as 22 is provided in the rib cam box at the or each design feed, and similarly a welt cam such as 24 is provided in the bottom cam box at the or each plain feed, said cams being adapted, when withdrawn, to admit the corresponding slider butts to non-knitting or welt tracks 23 and 24 so that knitting is suspended on the corresponding needles at the time required for any desired number of courses for the purpose of forming a welt.

In accordance with the present invention the machine is furnished with pelerine stitch mechanism of the character described in the specification of co-pending United States application Serial No. 393,614, which resulted in Patent No. 2,286,806, and also with lap or wrap striping mechanism of the form described in the specification of co-pending United States application Serial No. 404,923, which resulted in Patent No. 2,292,941. In this connection there is a plurality of transfer instruments 25 interspersed with lap or wrap thread guides 26 in the same bed or carrier 27. As shown in Figure 1, this bed or carrier consists of a horizontally disposed dial which is mounted within the needle cylinders 2 and 3 concentrically therewith. The dial 27, moreover, is of ring-like form and attached at its inner periphery to the rim portion 28a of a wheel 28. The central hub portion of this wheel is perforated as at 28b (Figures 1 and 3) to assist in guiding the embroidery threads *et al* to the thread guides 26 from bobbins, cones, spools or reels (not shown) carried by a structure arranged above the top plate 29 of the machine. The wheel 28 is secured to the lower end of a central spindle 30 associated with the said overhead structure. The upper face of the dial 27 is formed with radial tracks or grooves 27a (Figures 1 and 2) for reception of the transfer instruments 25 and the thread guides 26. Instead of being interspersed in the dial, the said instruments and guides may be arranged in definite groups or panels. In any event, the dial 27 is formed at its outer periphery with a flange 27b to enable it to be additionally supported between an annular support 31 and a clamping ring 32 which latter are secured together by screws 33. The annular support 31 is also flanged at 31a so as to enable 75 39a which can be readily broken off according

5 it to be arranged for movement circumferentially between two superposed supporting rings 34 and 35 attached both to each other and to the lower end of the rib cylinder 3. This construction is such as to enable the instruments and guides in the dial 27 to be shogged in relation to the needle cylinders by mechanism hereinafter to be described. The dial 27 normally rotates with the said cylinders and is located at such a level

10 that the operative extremities of the transfer instruments 25 and thread guides 26 are projectable and retractable in the space between the opposed needle cylinders, that is to say, in this particular instance, between the clamping ring 32 and the nibs 36a of inside sinkers or 15 web holders 36 associated with the plain cylinder 2.

15 As will be appreciated from a consideration of Figures 2 and 3, each of the transfer instruments 25 is of blade-like form and at its operative end 25a is laterally offset so as to have an arched formation the opposite ends of which are in alignment with the remainder of the blade. The tip of the instrument is in the form of a 20 nib 25b and the instrument also has a loop engaging shoulder 25c (Figure 2) at a suitable distance from the tip. The upper edge of the instrument is so formed as to provide thereon an operating butt 25d for engagement with suitable operating cams presently to be described. 25 If desired, and as shown in Figure 3, the transfer instruments may be used in pairs *i. e.* left hand and right hand, so as to enable a loop thereon to be spread laterally in opposite directions for transference to adjoining needles 4.

30 Each of the thread guides 26 is also of blade-like form and, as shown in Figure 1, is recessed at 26a at its lower edge in the region of its operative end suchwise as to provide at said end a downwardly directed right-angular extension 26b which is laterally bent in the manner depicted in Figure 3. This extension is thereby obliquely disposed with respect to the main portion of the guide, and has formed therein two 35 thread receiving holes 37 disposed one above the other. A further hole 38 is formed in that portion of the guide adjacent to the extension 26b. As in the case of the transfer instruments, the upper edge of each thread guide 26 is so formed as to provide thereon an operating butt 26c, but whereas the butts 25d on the transfer instruments are short, the butts 26c on the thread guides are long for a purpose hereinafter 40 to be explained.

45 55 In association both with the transfer instruments 25 and the thread guides 26 there are provided selector jacks 39 with selecting butts 39a thereon suchwise that when assembled the selectors present banks or groups of butts respectively in different planes for action upon by 50 respective selecting cams 40 and 41 (see more particularly Figure 3). Each of the instruments and guides is cut away as at 42 (Figure 2) on its underside to accommodate the corresponding selector jack 39 and to present a shoulder 43 against which the forward end of the said selector can act. At its rear end each of the selector jacks is formed with a right-angular extension 39b upon which the selecting butts 39a are formed. These butts are provided at respectively different levels 55 so as to be located in correspondingly different planes heightwise. If desired, and as shown in Figure 1, the selector jacks may initially be formed with a full complement of frangible butts 60 65 70 75 80 85 90 95 100 105 110 115 120 125 130 135 140 145 150 155 160 to requirements. At each feed of the machine the cam 40 is provided for selecting transfer instruments 25, whereas the cam 41 serves to select thread guides 26. Each of these selecting cams is horizontally disposed and movable vertically into different planes. For convenience in operation, however, the selecting butts 39a are divided into upper and lower groups R and S, the butts of one of these two groups serving the transfer instruments and the butts of the other group serving the thread guides. Thus, the movements of the selecting cams 40 and 41 at each feed are restricted, each cam being movable only to such an extent as to enable it to be moved into any one of the planes of the butts in the corresponding group. By this safeguard it is consequently impossible to effect a selection either of the transfer instruments or of the thread guides by the wrong selecting cam.

Alternatively, instead of providing selector jacks, the selecting butts may be provided directly on the instruments and guides themselves.

In any event, each of the selecting cams 40 and 41 is attached to the lower end 44a of a vertically disposed operating rod 44 which is suitably influenced by a compression spring 45 and arranged to slide within an upwardly projecting annular flange 46a formed on a stationary dial cam plate 46. The operating rods extend to the top of the machine and are pattern controlled through any suitable intermediate connections from a device or unit all substantially as described in prior specification No. 404,923 aforesaid.

The dial cam plate 46 is fixedly supported immediately above the dial 27 and on its underside is furnished with cams for action on the operating butts of the transfer instruments and thread guides. The underside of the cam plate and the tricked face of the dial are closely opposed, the cam plate being anchored by a link 47 (Figure 3) one end of which is fixed by a screw 48 to the flange 46a aforesaid, while the other end is secured by a screw 49 to a lug or like part such as 50 on the fixed supporting ring indicated at 51 in Figure 1. The last mentioned ring is rigidly secured in any suitable manner to the lower end of a sleeve 29a which is integral with and depends from the top plate 28.

All of the operating butts 25d and 26c are normally located in a common track from which they are diverted selectively by the respective selecting cams for admission to dial cam systems whereby the requisite advancing and retracting movements are imparted to selected instruments 25 and guides 26, and to which track the said butts are eventually returned for re-selection. This will be clear from a consideration of Figure 3 wherein it will be observed that the common track, which is indicated at 52, is concentric with respect to the central axis of the machine. Fully retracted transfer instruments 25 with their operating butts 25d in the track 52 are shown at T. Assume now that the selecting cam 40 at either of the feeds J or J¹ is rendered operative to select transfer instruments at that feed, then the said cam will act on the appropriate butts 39a and thereby push forward the corresponding selector jacks 39 suchwise as to effect partial advancement of the desired instruments (at the location marked V in each of Figures 3 and 5) to an extent just sufficient to enable yarn y to be collected, i. e. laid over, their nibs 25b and to direct their operating butts 25d into a track 53. Partially advanced transfer instruments are

shown at V, and at this stage in the knitting operation the nibs of such instruments function as sinkers over which sinker loops are drawn in the manner indicated at s1 in Figure 5. The said track 53, which for convenience may be termed the collecting track, determines the extent of the endwise movement of partially advanced transfer instruments and maintains the latter in this position until the operating butts 25d concerned are eventually acted upon by a cam 54 which functions fully to advance the selected instruments to the extent shown at the location marked W. By reason of such advancement, sinker wale loops previously drawn over the nibs 25b are caused to slide back along the instruments until they are caught and held by the loop engaging shoulders 25c. In this way the sinker wale loops are spread laterally suchwise as to enable them to be readily penetrated by rising plain needles. A sinker wale loop s1 which has been spread laterally in opposite directions by a pair of instruments for transference to two successive plain needles 41 is depicted in Figure 5. Immediately after the operating butts 25d of selected transfer instruments leave the cam 54, they are acted upon by a cam 55 and returned to the common track 52 with the result that the instruments are withdrawn to their original positions for re-selection. Distended sinker wale loops are thereupon left on the appropriate plain needles and subsequently meshed with knitted loops in needle wales to form pelerine stitches in a manner well known to those acquainted with the knitting art. In the case of a multi-feeder machine, selected transfer instruments may collect yarn and have sinker loops drawn over them more than once at the locations V of successive feeds before transferring the loops to needles at a location such as W. Thus, in the specific example illustrated, there is only one advancing cam 54, this being provided at the transfer feed J. Consequently, if only a single loop was required to be collected on an instrument 25, then that instrument would be selected at the said transfer feed. But if two loops were required on an instrument the latter would have to be selected at the first feed (J¹) in advance of the transfer feed suchwise as to enable the instrument to collect one loop at each of the two feeds J¹ and J before transference at the location W, and so on—depending on the number of loops to be collected, and the number of feeds available. Although the simple arrangement shown includes only one advancing cam 54 with its associated retracting cam 55, it is to be understood that cams of this character movable into and out of operation according to requirements may, if desired, be provided at each feed. Referring now to the lap or wrap thread guides 26, it will be seen that when such guides are fully withdrawn (as at X, Figure 3) their long operating butts 26c are in the common track 52. If, therefore, the selecting cam 41 at a feed is rendered operative it will act on appropriate butts 39a and so actuate the corresponding selector jacks 39 as to move desired guides 26 radially outwards to an extent sufficient to land their operating butts 26c onto an advancing cam 56. This cam will thereupon fully project the selected guides to carry their embroidery threads et across the needle circle from the inside to the outside thereof, after which a retracting cam 57 by contact with the butts 26c will withdraw the projected guides radially inwards to their original positions and thereby restore the said butts to the common track 52.

for re-selection. In this known manner each of the selected guides laps or wraps its thread around the adjacent plain needle, the relative lateral deflection between the guide and the said needle effected by the coaction of the latter with the laterally bent extremity 26b of the guide during its radial movements serving to facilitate the wrapping action. The advancing and retracting cams 56 and 57 at each feed are of less thickness than the remaining cams carried by the dial cam plate 46 so that they will miss the short operating butts 25d on the transfer instruments. Consequently whenever butts 25d are travelling in the collecting track 53 they can safely pass beneath the cams 56 and 57 without interference therefrom.

At the feed J (or at each feed of the machine where plain needles are to receive expanded sinker loops) the plain cylinder cam system M, as shown in Figure 5, includes an adjustable plain stitch cam 58, an associated so-called feeder cam 59 for directing the knitting butts 7 of the bottom sliders 5 into the range of the said stitch cam, a cam 60 for raising plain needles to tucking height in order to open their latches, a cam 61 just in advance of the location W for lowering said needles again so that selected transfer instruments 25 can be safely advanced over them by the cam 54 at the feed, and a cam 62 for raising needles to such a height as to pass them through expanded sinker wale loops on appropriate transfer instruments. The embroidery thread wrapping position, which is indicated at Y in Figure 5, is at the latch guard 63 in advance of the plain stitch cam 58.

At the point W where transfer instruments 25 are fully advanced at the or each feed, the appropriate sinker or web holder 36 is formed with a front portion 36b of such angular form as to prevent expanded loops from sliding beneath the said sinker or web holder at such times as the latter moves forward. In Figures 7 and 8 such a sinker is shown in its retracted and advanced positions respectively.

To enable the transfer instruments 25 and the thread guides 26 to be projected between the lower end of the rib cylinder 3 and the nibs of the inside sinkers or web holders 36, it is necessary to provide a fairly considerable space between these parts. This can be done either by omitting a verge which would normally be associated with the rib cylinder or by appropriately shortening the latter. In either event, in lieu of the customary verge or verge portion, there are provided independently slidable "top sinkers" or knocking-over bits such as 64 (Figure 1) which are mounted in the lower end of the rib cylinder and furnished with operating butts 64a to enable them to be rendered operative seriatim during the production of purl stitches or rib knitting. For the purpose of holding down the fabric at such times as loops are being drawn by rib needles each of the top sinkers or knocking-over bits 64 is formed at its lower end with an inwardly directed radial extension 64b. These extensions are disposed at right angles to the main portions of the sinkers or bits and are of such length as effectively to prevent purl or rib loops drawn over them from becoming displaced and sliding up along the back edges thereof. For operating the top sinkers or bits 64 there is provided below the rib stitch cam 14 at each feed a cam 65 for action upon the butts 64a to depress same seriatim at the stitch drawing location. A cam 66 disposed immediately beneath the top sinker cam 65 serves to

guard the butts 64a during depression of the sinkers or bits 64 and, immediately thereafter, to raise said butts again in an idle track 67.

A hinged door 68, provided in the fixed cam plate 46, is adapted to be positively opened and closed by means of a screw 69 operable through a rod 70 from a readily accessible part of the machine, the door when opened providing a space for the insertion or removal of transfer instruments and thread guides into and from the dial 27. The door 68 fits in a recess 46b formed in the cam plate 46 and is arranged to turn on a hinge pin 71 which latter is formed at its opposite ends with ears 71a by which it is secured by screws 72 (Figure 3) to the said plate. The cam 56 at the appropriate feed is attached to the underside of the door by a screw 73 and is consequently withdrawn—at least partially—from the cam plate whenever the door is opened. In this connection the cam plate is also formed with an opening 46c of such shape and size as to permit of withdrawal of the cam 56. The screw 69, the lower end of which is appropriately formed for engagement with the end of the door remote from the hinge pin 71, extends up through the flange 46a and is adapted for co-operation with the rod 70 in the manner shown in Figure 4.

Means may be furnished in the machine for effecting shogging movement of the transfer instruments or/and the lap or wrap thread guides and the appropriate needle bed, one in relation to the other, i. e. varying the relative positions of the instruments or guides and the associated needles laterally so as further to diversify the transfer effect or/and so that different threads may be supplied to the same needles in order to produce contrasting, e. g. different coloured, effects in the same needle wales. For instance, in a circular knitting machine of the characteristic type aforesaid this result may be achieved by shogging the said instruments or/and thread guides circumferentially over one or more needles. In the specific example illustrated, provision is made for shogging the dial 27 so as to shog both the transfer instruments 25 and the thread guides 26 circumferentially over one or more plain needles. The shogging mechanism employed will now be described with reference to Figures 1, 9 and 10. This mechanism includes a stepped cam 74 which is mounted to turn about a fixed vertical stub axle 75 carried by a bracket 76 attached to the top of the upper dial-supporting ring 35. To prevent it from turning too freely about the stub axle 75 the cam 74 is recessed at 74a to house a member 77 which is arranged to produce friction or impart pressure between the said cam and the upper end of the stub axle. A small plate 78 serves to maintain the friction or pressure member 77 in position. The cam 74 is formed with a plurality of stepped formations 74b half of which slope downwardly in one direction while the remainder similarly slope in the opposite direction (see Figure 9). Mounted beneath the stepped cam is a disc cam 79 a portion of the periphery of which is formed with a series of contiguous shallow recesses 79a. The disc cam is connected with the stepped cam so as to turn therewith, and provision is made for relative adjustment between these two cams. Thus, the said cams are connected together by means of a vertically disposed adjustable pin 80 which extends right through the stepped cam 74 and is formed or provided at its lower end with an eccentrically disposed or cranked portion 80a arranged to project downwardly into a slot 79b formed in the disc cam 79.

(Figure 1). A saw cut is formed in the upper end of the connecting pin 80 to enable it to be turned, and a grub screw 81, inserted in the stepped cam, serves to set the pin 80 securely in position after adjustment. Thus, by turning the pin 80 in one direction or the other, the disc cam 79 can be advanced or retarded slightly and thereby accurately set with respect to the stepped cam 74. Immediately above the stepped cam is located a block 82 through which extend a pair of spaced rod-like plungers or tappets 83 and 84 (Figure 1) arranged for action upon the stepped formations 74b. This block is carried by the fixed supporting ring 51. One of the plungers or tappets, 83, is longer than and connected with the shorter plunger or tappet 84 by means of a connecting link 85. This link is pivoted centrally upon a lug 82a formed on the block 82 so that when one of the plungers or tappets is depressed the other is raised, and vice versa. The plunger or tappet 83 extends to the top of the machine and is pattern controlled, being movable up or down to varying extents according to the extent and direction of the shogging movement to be imparted to the dial 27. The arrangement is such that upon downward movement of one of the tappets or plungers by action thereof upon the appropriate part of the stepped cam 74, the latter and hence also the disc cam 79 will be turned to the required extent in one direction, whereas upon similar movement of the other tappet or plunger the stepped and disc cams will be turned in the reverse direction. Screw and slot connections are provided between the plungers or tappets 83 and 84 and the connecting link 85. Referring to Figures 9 and 10 it will be seen that the disc cam 79 is arranged for action upon rolls 86 carried by an arcuate slide 87 which is mounted for movement within a recess 76a (Figure 1) formed in the bracket 76. Retaining strips 88 and 89 attached to the top of the bracket 76 serve to prevent heightwise displacement of the slide 87. A lug or like part such as 90 is secured to the annular support 31 and connected to the slide 87 by means of an adjustable eccentric pin 91. Each roll 86 is of such size that it will seat in one of the shallow recesses 79a in the disc cam 79. As will be appreciated, the construction and arrangement of the shogging mechanism is therefore such that by effecting movement of the disc cam to a required extent in one direction or the other, the slide 87 will be correspondingly operated to impart a shogging movement to the dial 27.

If, as may be, the transfer instruments and thread guides are mounted in separate beds or carriers, the shogging mechanism may be employed only in conjunction with the lap or wrap striping mechanism.

Instead of being actuated by slidable jacks such as 39, the thread guides 26 may alternatively be adapted for engagement near their operative ends with selectively operated pivoted jacks. Or the main portions of the thread guides themselves may be arranged substantially axially of the needle cylinders and movable radially for wrapping their threads around desired needles in the manner described in United States specification No. 2,065,469.

Since, as already alluded to herein, it may be desired to form separating or parting courses, e. g. on plain needles, or to supply a draw thread, any conventional means suitably controlled and operated may be adopted in the improved machine for this purpose.

Provision may also be made in the machine for varying the quality of the fabric, e. g. for knitting areas with purl effects and open stitch effects with or without embroidery effects slacker than rib courses, and in a circular machine such means may be of the form disclosed in the aforesaid specification No. 391,212.

As will be understood, the needles of the machine, the transfer mechanism and the thread lapsing or wrapping mechanism may be so controlled as to enable the purl stitch effects and the additional effects to be restricted to a particular area or areas, and an area or areas of plain stitch fabric or any conventional stitch variation, such as tuck effects, miss-stitch effects, mock rib effects, or combination of stitch variations, as well understood in the art, or/and ordinary or fancy ribbed effects with or without welts and separating or parting courses or the introduction of draw threads, to be produced in desired longitudinal sequence.

If desired, the machine may include means for effecting shogging movement of the needle beds one in relation to the other so as to enable racked rib and like effects to be produced.

What we claim then is:

1. A knitting machine comprising, in combination, at least two needle beds, needles for operation in each of said beds, means for supplying main yarn to said needles, means for operating needles suchwise as to cause them to produce purl stitch effects, means for operating needles to form loops from said yarn, independently operable loop transfer instruments associated with the needles and over which some of the loops can be drawn, the said instruments being arranged to work in pairs and one of the instruments of each pair being formed at its operative end with a loop expanding portion offset laterally to the right-hand side whereas the companion instrument of the pair is formed at the corresponding end with a similar loop expanding portion offset laterally to the left-hand side, means for effecting co-operative operation of the loop transfer instruments and needles suchwise as to enable a loop to be spread laterally in opposite directions on the loop expanding portions of any desired pair of transfer instruments and transferred to two adjoining needles, and means for feeding embroidery threads to desired needles and causing the latter to take said threads.

2. A knitting machine comprising, in combination, at least two needle beds, needles for operation in each of said beds, means for supplying main yarn to said needles, means for operating needles suchwise as to cause them to produce purl stitch effects, means for operating needles to form loops from said yarn, independently operable loop transfer instruments associated with the needles and over which some of the said loops can be drawn, means for effecting co-operative operation of the loop transfer instruments and needles to enable a loop to be transferred laterally from any desired transfer instrument to an adjacent needle, a plurality of individually operable lap thread guides for feeding embroidery threads to needles, means for operating said guides and for actuating needles so that desired embroidery threads are lapped around corresponding needles, means for selecting the transfer instruments, other means for selecting the thread guides, and, in association with said instruments and guides, jacks provided with patterning butts disposed so that when the jacks are assembled they present groups of such butts re-

spectively in different planes for action upon by the respective selecting means.

3. A knitting machine comprising, in combination, at least two needle beds, needles for operation in each of said beds, means for supplying main yarn to said needles at at least one feeding station, means for operating needles suchwise as to cause them to produce purl stitch effects, other means for operating needles to form loops from said yarn, independently operable loop transfer instruments associated with the needles and over which some of the said loops can be drawn, means for effecting co-operative operation of the loop transfer instruments and needles to enable a loop to be transferred laterally from any desired transfer instrument to an adjacent needle, a plurality of individually operable lap thread guides for feeding embroidery threads to needles, means for operating said guides and for actuating needles so that desired embroidery threads are lapped around corresponding needles, jacks which are provided in association with the transfer instruments and the thread guides and furnished with patterning butts in different planes, there being one group of said butts for the transfer instruments and another group for the thread guides, and, at the aforesaid feeding station, two selecting cams for action selectively upon the patterning butts of the respective groups, each of said cams being movable but only to such an extent as to enable it to be moved into any one of the planes of the butts in the corresponding group.

4. A knitting machine comprising, in combination, at least two needle beds, needles for operation in each of said beds, means for supplying main yarn to said needles, means for operating needles suchwise as to cause them to produce purl stitch effects, means for operating needles to form loops from said yarn, independently operable loop transfer instruments furnished with operating butts and over which some of the loops can be drawn, a cam system comprising cams for action on said butts to impart advancing and retracting movements to the transfer instruments, means for actuating needles in conjunction with said instruments suchwise as to enable a loop to be transferred from any desired transfer instrument to at least one adjacent needle, a plurality of individually operable lap thread guides which are also furnished with operating butts and adapted to feed embroidery threads to needles, a further cam system comprising cams for action upon the operating butts of the thread guides to advance and retract the latter in conjunction with operation of the needles so that desired embroidery threads are lapped around corresponding needles, selecting means for effecting selection of those transfer instruments and guides to be operated by the cams as aforesaid, and parts providing a common track in which all of the operating butts are normally located, from which said butts are selectively diverted by the selecting means for admission to the cam systems and to which the said butts are eventually returned for re-selection.

5. A knitting machine comprising, in combination, at least two needle beds, needles for operation in each of said beds, means for supplying main yarn to said needles, means for operating needles suchwise as to cause them to produce purl stitch effects, means for operating needles to form loops from said yarn, independently operable loop transfer instruments associated with the needles and over which some of the loops

can be drawn, means so arranged and operable as only partially to advance selected transfer instruments to an extent sufficient for the said instruments to collect, i. e. receive, without expanding loops of said yarn, means for subsequently effecting co-operative operation of said selected transfer instruments and appropriate needles suchwise as to enable the collected loops to be expanded and transferred laterally to said last mentioned needles, and embroidery mechanism for feeding embroidery threads to desired needles and causing the latter to take said threads.

6. A knitting machine comprising, in combination, at least two needle beds, needles for operation in each of said beds, means at each of a plurality of feeding stations for supplying main yarn to said needles, means for operating needles suchwise as to cause them to produce purl stitch effects, means for operating plain needles to form loops from said yarn, independently operable loop transfer instruments furnished with operating butts and over which some of the loops can be drawn, selecting means at each feeding station for effecting partial advancement of selected transfer instruments to an extent sufficient for the said instruments to collect, i. e. receive, without expanding loops of said yarn, parts providing a track common to all of the feeding stations and to which the operating butts on selected transfer instruments are directed, cam means at one only of said feeding stations for fully advancing said selected instruments so that the loops collected thereon are expanded, means for actuating appropriate needles so as to cause them to penetrate and receive the expanded loops, and embroidery mechanism for feeding embroidery threads to desired needles and causing the latter to take said threads.

7. A knitting machine comprising, in combination, at least two needle beds, needles for operation in each of said beds, means at each of a plurality of feeding stations for supplying main yarn to said needles, means for operating needles suchwise as to cause them to produce purl stitch effects, means for operating plain needles to form loops from said yarn, independently operable loop transfer instruments furnished with operating butts and over which some of the loops can be drawn, selecting means at each feeding station for effecting partial advancement of selected transfer instruments to an extent sufficient for the said instruments to collect, i. e. receive, without expanding loops of said yarn, parts providing a track common to all of the feeding stations and to which the operating butts on selected transfer instruments are directed, cam means for fully advancing said selected instruments so that the loops collected thereon are expanded and for thereupon retracting said instruments, means for actuating appropriate needles so as to cause them to penetrate and receive the expanded loops, a plurality of individually operable lap thread guides which are also furnished with operating butts and adapted to feed embroidery threads to needles, a further cam system comprising cams at each feeding station for action upon the operating butts of the thread guides to advance and retract the latter in conjunction with operation of the needles so that desired embroidery threads are lapped around corresponding needles, additional selecting means at each feeding station for effecting selection of those lap thread guides to be operated by the

appropriate cams at that station, and parts providing a common track in which all of the operating butts on the transfer instruments and thread guides are normally located, from which said butts are selectively diverted by the respective selecting means for admission to the cam systems and to which the said butts are eventually returned for re-selection.

8. A knitting machine as claimed in claim 7, wherein the operating butts on the transfer instruments and those on the thread guides are of respectively different lengths (long and short) and the cams for action on the long butts are of less thickness than the remaining cams, for the purpose herein specified.

9. A knitting machine comprising, in combination, at least two needle beds, needles for operation in each of said beds, means for supplying main yarn to said needles, means for operating needles suchwise as to cause them to produce purl stitch effects, means for operating plain needles of the machine to form loops from said yarn, transfer instruments independently operable in conjunction with plain needles to effect lateral transference of desired loops to appropriate needles, a carrier in which said transfer instruments are arranged, a plurality of individually operable lap thread guides for feeding embroidery threads to needles, said guides being mounted for operation in the same carrier as the transfer instruments, means for so operating said guides and actuating needles that desired embroidery threads are lapped around appropriate needles, a hinged door which is provided in association with the said carrier and adapted when opened to provide space for the insertion and removal of transfer instruments and lap thread guides into and from the carrier, and screw means for positively opening and closing the door.

10. A knitting machine comprising, in combination, opposed plain and rib needle beds, needles for operation in each of said beds, inside holding down sinkers in the plain needle bed, means for moving said sinkers back and forth in timed relation with actuation of needles, means for supplying main yarn to said needles, means for operating needles suchwise as to cause them to produce purl stitch effects, means for operating plain needles to form loops from said yarn, independently operable loop transfer instruments associated with said plain needles and over which some of the loops can be drawn, means for advancing and retracting loop transfer instruments in conjunction with actuation of appropriate plain needles to enable loops to be expanded by desired transfer instruments and transferred laterally from the latter to adjacent needles, the front portion of the holding down sinker at the point where transfer instruments are advanced for the transference of loops being of angular form to prevent expanded loops from sliding beneath the said sinker at such times as it moves forward, and means for feeding embroidery threads to desired needles and causing same to take said threads.

11. A knitting machine comprising, in combination, two opposed needle beds, needles for operation in each of said beds, means for supplying main yarn to said needles, means for operating needles suchwise as to cause them to produce purl stitch effects, means for operating needles to form loops from said yarn, independently operable loop transfer instruments associated with the needles in one of the beds and over which some of the loops can be drawn, means for

effecting co-operative operation of the loop transfer instruments and appropriate needles suchwise as to enable a loop to be transferred laterally from any desired transfer instrument to at least one adjacent needle, a plurality of individually operable lap thread guides for feeding embroidery threads to needles, means for operating said guides and for actuating needles so that desired embroidery threads are lapped around corresponding needles, and means for effecting shogging movement of at least the lap thread guides and the appropriate needle bed, one in relation to the other, for the purpose herein described.

12. A knitting machine comprising, in combination, a plain needle cylinder, an axially opposed rib needle cylinder, double-ended needles for operation in said cylinders, means for supplying main yarn to said needles, instrumentalities for actuating said needles, means adapted for action upon said needle-actuating instrumentalities suchwise as to effect transference of needles from one bed to the other and thereby enable the machine to produce purl stitch effects, means for operating plain needles to form loops from the said yarn, independently operable loop transfer instruments associated with plain needles and over which some of the loops can be drawn, means for effecting co-operative operation of the loop transfer instruments and plain needles suchwise as to enable a loop to be transferred laterally from any desired transfer instrument to an adjacent plain needle, a dial in which the transfer instruments are arranged, said dial being mounted within the needle circle concentrically therewith, a plurality of individually operable lap thread guides which are also arranged in the said dial for feeding embroidery threads to needles in the plain cylinder, means for operating said guides and for actuating plain needles so that desired embroidery threads are lapped around corresponding plain needles, and means for shogging the dial circumferentially to the extent of at least one needle in the plain cylinder, for the purposes herein specified.

13. A knitting machine comprising, in combination, a plain needle cylinder, an axially opposed rib needle cylinder, double-ended needles for operation in said cylinders, means for supplying main yarn to said needles instrumentalities for actuating said needles, means adapted for action upon said needle-actuating instrumentalities suchwise as to effect transference of needles from one bed to the other and thereby enable the machine to produce purl stitch effects, means for operating plain needles to form loops from the said yarn, independently operable loop transfer instruments associated with plain needles and over which some of the loops can be drawn, means for effecting co-operative operation of the loop transfer instruments and plain needles suchwise as to enable a loop to be transferred laterally from any desired transfer instrument to an adjacent plain needle, a dial in which the transfer instruments are arranged, said dial being mounted within the needle circle concentrically therewith, a plurality of individually operable lap thread guides which are also arranged in the said dial for feeding embroidery threads to needles in the plain cylinder, means for operating said guides and for actuating plain needles so that desired embroidery threads are lapped around corresponding plain needles, and mechanism for effecting turning movements of the dial in-

dependently of the needle cylinders, said mechanism comprising a disc cam fixedly supported in relation to the needle cylinders, a stepped cam which is connected to the said disc cam, pattern controlled plungers arranged for action upon the stepped cam to turn the latter and hence also the disc cam to a desired extent in one direction or the other, and a slide which is attached to the dial and furnished with rollers for action upon the disc cam whereby the said dial can be shogged to the extent required in one direction or the other.

14. A circular knitting machine comprising, in combination, a plain needle cylinder, an axially opposed needle cylinder, double-ended needles for operation in said cylinders, means for supplying main yarn to said needles, sliders for actuating the needles, means for operating the sliders to transfer needles from the plain cylinder

5 to the opposite cylinder thereby to produce purl stitch effects, means for operating needles to knit the main yarn, a dial mounted concentrically with the cylinders, independent loop transfer instruments operable in said dial for reception of loops of the main yarn, means for effecting conjoint operation of the loop transfer instruments and associated needles suchwise as to enable a loop to be transferred laterally from 10 any desired loop transfer instrument to an adjacent needle, a plurality of individually operable lap thread guides also operatively arranged in said dial for feeding embroidery threads to appropriate needles, and means for so operating 15 said guides that their embroidery threads are lapped around desired needles.

HENRY HAROLD HOLMES.
JOHN CYRIL HERBERT HURD.
